UNITED STATES PATENT OFFICE.

WILLIAM JAMES LANE AND GEORGE LANE, OF POUGHKEEPSIE, NEW YORK.

MOTOR-VEHICLE.

SPECIFICATION forming part of Letters Patent No. 690,371, dated December 31, 1901.

Application filed May 8, 1901. Serial No. 59,327. (No model.)

To all whom it may concern:

Be it known that we, WILLIAM JAMES LANE and GEORGE LANE, citizens of the United States, residing at Poughkeepsie, county of Dutchess, State of New York, have invented certain new and useful Improvements in Motor-Vehicles, of which the following is a specification.

Our invention relates to motor-vehicles of the type adapted to be operated by steam.

Our invention consists in a special arrangement for the flues through which the products of combustion from the burner passing the boiler are discharged from the vehicle.

15 The object of our invention is to discharge the products of combustion from the burner in a downward direction and rearwardly of the vehicle whether the vehicle be at rest or in motion.

20 The accompanying drawings, which show two constructions by which our invention may be carried into effect, will serve to illustrate our invention, and in which—

25 Figurè 1 is a longitudinal section taken through a motor-vehicle and showing a water-tank, boiler, and engine with its connection in elevation and a portion of the escape-flues for the products of combustion in section. Fig. 2 is a plan view. Fig. 3 is a section corresponding to Fig. 1, but showing a modification. Fig. 4 is a plan view of Fig. 3.

In the drawings, 10 represents the body of a motor-vehicle. Any suitable shape or construction of body may be made use of.

35 11 is a vertical-tube boiler, 12 a burner located under boiler, and 13 a horizontal flue situated over the boiler and communicating with the downwardly-directed flues 14 and 15, Figs. 1 and 2, and 14^a and 15^a, Figs. 3 and 4.

40 In Figs. 1 and 2 the downwardly-directed flue 14 is divided to form two flues, situated, preferably, at opposite sides of the front of the boiler and connected at their bottom with a transverse flue 16, which is connected to

45 and adapted to discharge into a longitudinal flue 17. The flue 14^a in Figs. 3 and 4 is a single flue and located at one side of the back of the boiler and adapted to discharge below the vehicle. The flue 15 in Figs. 1 and 2 is carried directly backward from the horizontal flue 13 and then turned downward at its outer

In Figs. 3 and 4 the flue 15 is carried backward from the horizontal flue 13 and turned down at its outer end; but between the flues 55 13 and 15^a there is arranged a deflecting-plate 18, whose vertical axis corresponds to the axis of the flue 14^a.

19 is a steam motor device, 20 a live-steam pipe from boiler to motor device, and 21 an exhaust-steam pipe leading from motor device and discharging into one of the escape-flues for the products of combustion.

In Figs. 1 and 2 the exhaust-pipe discharges into the flue 17 and in Figs. 3 and 4 into the 65 horizontal flue 13.

The operation of the device will be readily understood. When the vehicle is at rest, the products of combustion passing the boiler are discharged through the flue 15 or 15^a; 70 when the vehicle is in motion and aided by the injector action of the exhaust-steam from the pipe 21, through the downwardly-carried flue 14 and its connecting-flues 16 and 17, Figs. 1 and 2, or through the downwardly- 75 carried flue 14^a, Figs. 3 and 4.

By the arrangement of flues described all products of combustion passing the boiler will be caused to traverse a downward path when passing from the horizontal flue over 80 the boiler to and being discharged into the atmosphere.

The advantages of this construction are that the heated products of combustion will be discharged at the rear of the vehicle and 85 in planes where they will not be picked up by moving air-currents, especially those moving from the rear of the vehicle, and driven directly upon the occupants of the vehicle. Thus the objectionable features of heat and 90 unpleasant odors from the products of combustion now common with motor-vehicles where the products of combustion are discharged partially in a downward direction and partially in an upward direction are done 95 away with.

Having thus described our invention, we claim—

1. In a motor-vehicle, the combination of a boiler, a horizontal flue located over the boiler, 100 and two downwardly-discharging flues connected to said horizontal flue.

2. In a motor-vehicle, the combination of a boiler, a horizontal flue located over the boiler,

two downwardly-discharging flues, and means for increasing the draft in one of said flues.

3. In a motor-vehicle, the combination of a boiler, a horizontal flue located over the boiler, 5 and two downwardly-discharging flues connected to said horizontal flue and having their discharge-openings located in different planes.

4. In a motor-vehicle, the combination of a boiler, a horizontal flue located over the boiler, 10 a short flue carried from the back of the horizontal flue and discharging downwardly, a pair of flues situated in front of the boiler and connected to the horizontal flue, said flues connected at their lower ends to a transverse flue, and said transverse flue to a longitudinally-disposed downwardly-discharging flue. 15

5. In a motor-vehicle, the combination of a

boiler, a horizontal flue located over the boiler, a rearwardly-projecting downwardly-discharging flue connected to said horizontal flue, 20 a pair of vertical flues connected to the horizontal flue, a transverse flue connected to the vertical flues, a longitudinally-disposed flue connected to the transverse flue, and an exhaust-pipe discharging into said longitudinal flue. 25

In testimony whereof we affix our signatures in the presence of two witnesses.

WILLIAM JAMES LANE.
GEORGE LANE.
